INVENTOR.
J. W. WALKER
BY Milton S. Grindall,

ATTORNEY

UNITED STATES PATENT OFFICE.

JAMES W. WALKER, OF SIOUX CITY, IOWA.

STAPLE-PLIERS.

1,265,842.

Specification of Letters Patent.

Patented May 14, 1918.

Application filed June 12, 1916. Serial No. 103,094.

To all whom it may concern:

Be it known that I, JAMES W. WALKER, a citizen of the United States, and a resident of Sioux City, in the county of Woodbury 5 and the State of Iowa, have invented a certain new and useful Improvement in Staple-Pliers, of which the following is a specification.

The present invention relates to means for 10 clenching staples.

The invention has for its primary object the production of an improved means for clenching staples.

Another object of the invention is the 15 production of a tool particularly adapted for clenching staples in metal fence-posts.

A further object of the invention is the production of a tool adapted to either clench staples, or straighten clenched staples sufficiently to permit their removal.

A still further object of the invention is the production of a simple staple-clenching tool inexpensive in construction and requiring but a minimum of power to operate.

With these and other objects in view, the invention, consisting in the construction, combination and novel arrangement of parts, will be fully understood from the following description, reference being had 30 to the accompanying drawings which form a part of this application, and in which like characters of reference indicate corresponding parts throughout the several views, of which,—

Figure 1 is a plan of the preferred embodiment of the invention, as when applied to clench a staple in a steel fence-post;

Fig. 2 is a side elevation of the same, in closed position after clenching the staple, 40 one of the jaws and the post being cut away.

Fig. 3 is an inverted plan of the tool;

Fig. 4 is an end elevation of Fig. 1;

Fig. 5 is a plan of the tool applied as a 45 wire-stretcher;

Fig. 6 is a front elevation of the head-engaging jaw; and

Fig. 7 is a horizontal section of the same.

Although I have illustrated and herein- 50 after described the preferred embodiment of the invention I would not be understood as being limited to the specific structure chosen for illustration, for various alterations in the details of construction and arrangement of parts may be made without

departing from the spirit and scope of the invention, as defined in the appended claims.

Referring, now, to the illustrations, the tool is provided with pivoted handles, 8 and 9. The handle, 8, is formed with a lateral jaw, 10, preferably having a head, or enlarged end, 11, and the handle, 9, is formed with a lateral part, 12, oppositely disposed to the jaw, 10, and fulcrumed, as at 13, to the handle, 8.

The handle, 9, has a portion, 14, extending beyond the jaw, 10, and provided on its side with a staple-spreading head 15, preferably a cylinder normally extending substantially in parallelism with a jaw, 10, and somewhat greater in diameter than the distance between the points of the staples.

The head is preferably provided with a broad circumferential groove, 16, which serves to prevent lateral displacement of the 75 points of the staples when the tool is applied, as will presently appear.

The face of the enlarged part of the jaw, 10, is preferably inclined at an angle, so that when the tool is opened, as in Fig. 1, the said 80 face will be substantially parallel with the head, 15.

In the face of the jaw portion, 11, is a depression, 17, preferably so formed that it gradually increases in depth from a point 85 adjacent the end of the jaw, toward the fulcrum, and terminates rather abruptly to afford a shoulder, 18.

The portion of the face between the depression and the extreme end of the jaw is 90 provided with a longitudinal notch 19.

The handles are preferably oppositely offset, in order that their grips will be in the same plane to afford convenient operation.

One of the handles may be formed with a claw, 20, for drawing nails, staples, etc.; and the other formed with a screw-driver blade, 21.

The handle, 8, is formed with a cutting 100 ear, 22, which coacts with a similar oppositely-disposed member, 23, on the companion handle, to cut wire.

On the extended handle portion, 14, is a stud, 24, between which and a depression, 105 25, in the jaw, 10, a wire may be gripped.

When used to stretch fence wire, the heel of the jaw, 15, is engaged against the fence-post and the wire gripped as above described. Power is then applied to the 110

handle, 8, in the direction indicated by the arrow in Fig. 5.

Referring, now, to Figs. 1, 2 and 4, 26 is a familiar type of steel fence-post, provided with slots, 27, adapted to receive the usual staples, 28, which secure the wires, 29 to the posts.

In stapling a wire to a post, a staple is first placed over the wire and through the post as usual. The tool is then applied from the side of the post adjacent the wire, with the handle, 9, disposed at right angles thereto and with the extended portion, 14 adjacent the edge of the post, so that the clinching head, 15, will be in a position to enter between and spread the prongs of the staple. The handle, 8, is then moved laterally to admit the head of the staple into the depression of the jaw, 10, all as clearly presented in Fig. 1. The handles are then forced together, as shown in Fig. 2, whereupon the jaws coact in forcing the staple through the post and bending the prongs thereof laterally.

25 To sufficiently straighten the prongs of a staple thus clenched, to permit its removal, it is only necessary to grip the prongs between the jaw, 15, and the notch, 19, of the companion jaw, and force the prongs toward each other by pressure on the handles.

The head 15, is adapted to be used as a hammer peen.

Having thus described my invention, what I claim as new and desire to secure by Letters Patent of the United States, is,—

35 1. In a device of the class described, a staple spreading member comprising a cylinder greater in diameter than the width of the staple and having a grooved periphery 40 to receive the prongs of the staple.

2. In a staple-setting tool, a pair of relatively movable handles, a part on one handle adapted to engage the head of a staple, and

a cylindrical part on the other handle, having a peripherally grooved portion, said parts being movable relatively toward and from each other by movement of the handles, said cylindrical part being greater in diameter than the width of the staple, and the grooved portion being adapted to enter between and thereby spread the staple prongs when said parts are moved relatively toward each other.

3. In a stapling tool, a pair of pivoted handles, and jaws extending laterally from the handles and movable toward and from each other, the face of one of the jaws having a depression to receive the head of a staple and the other of said jaws being adapted to bend the prongs of the staple when jaws are moved relatively toward each other, the end of said first-described jaw being notched to receive one of the staple prongs to facilitate straightening of the prongs by engaging them between the jaws.

4. In a stapling tool, a pair of pivoted handles having jaws thereon movable toward and from each other, one of said jaws being engageable with the head of a staple and the other operable to spread the staple prong when the jaws are moved relatively toward each other, the end of one of the jaws being provided with a longitudinal notch to receive one of the prongs to facilitate straightening the prongs by engaging them between the jaws.

5. In a stapling tool, a pair of pivoted handles, a lateral jaw on one handle adapted to engage the head of a staple, and a convex lateral jaw on the other handle, movable relatively toward and from said first jaw and having a peripherally-grooved portion operable to spread the prongs of a staple.

In testimony whereof I have hereunto set my hand.

JAMES W. WALKER.
